Richard Oliver.

ATTORNEY

UNITED STATES PATENT OFFICE.

OTIS J. WISE, OF CHARLESTON, WEST VIRGINIA.

TOOTH-BRUSH.

1,288,349.

Specification of Letters Patent. Patented Dec. 17, 1918.

Application filed June 29, 1917. Serial No. 177,745.

To all whom it may concern:

Be it known that I, OTIS J. WISE, a citizen of the United States, residing at Charleston, in the county of Kanawha and State of West Virginia, have invented certain new and useful Improvements in Tooth-Brushes, of which the following is a specification.

My invention relates to new and useful improvements in a tooth brush and has for 10 its principal object the construction of the brush in such a manner that it may be easily cleaned.

Another object of the invention is the construction of the brush in sections where- 15 by the bristles may be separated for clean- ing.

A further object of the invention is the provision of means for separating the sec- 20 tions and means for returning the sections 20 into their original position after being cleaned.

With these and other objects in view, the invention consists in the novel details of construction and arrangement of parts which 25 will be more clearly understood from the following description and drawing, in which

Fig. 1 is a side elevation,

Fig. 2 a bottom plan partly in longitudinal section,

30 Fig. 3 an end view of the sliding rod for separating the sections, and

Fig. 4 a top plan, partly in longitudinal section, showing the sections open for cleaning.

35 In the drawings the numeral 1 indicates a casing closed at each end by means of plates 2 and 2', each of said plates having a square opening in the center and a round opening on either side thereof for the pur- 40 pose as will be presently described. Round rods 3 and 3' are rotatably mounted in the round openings in the end plates 2 and 2' and each of said round rods is provided with an extension 4 and 4' provided with bristles 45 5. The extensions extend beyond the end of the casing and each of the rods 3 and 3' is provided with a spiral groove 6 and 6', respectively, which is housed entirely within the casing. A square rod 7 is received in

50 the square openings in the end plates 2 and 2' and is provided with an extension 8 which lies between the extensions 4 and 4' as is more particularly illustrated in Figs. 2 and 4 of the drawings. The extension 8 is pro- 55 vided with bristles 9 which act with the

bristles 5 on the extensions 4 and 4' to make up a brush substantially of the same shape as tooth brushes now commonly in use. The extensions 4 are also round and, as is shown in the drawings, are of less diameter than 60 the rods 3 and 3' whereby a shoulder is formed, as indicated at 10 and 10', for en- gaging the inner face of the plate 2. The opposite ends of the rods 3 and 3' are re- 65 duced as indicated at 11 and 11' and are of such diameter that the rods may freely ro- tate within the casing.

A square sleeve 12 is adapted to pass through the square opening in the end plate 2' and over the end of the square rod 7 and 70 said sleeve carries a cross bar 13 having pins 14 and 14' depending from the under side thereof. These pins are adapted to enter the spiral grooves 6 and 6' formed in the round rods 3 and 3' so that when the sleeve 75 12 is moved longitudinally of the rod 7 the rods will be rotated. A coiled spring 15 surrounds the rod 7 between the end of the sleeve and the plate 2 and when the sleeve 12 is moved longitudinally of the rod 7 the 80 spring is compressed and when the sleeve is released it will be forced back to its original position.

When the brush is to be used for cleaning the teeth the several parts will be in the po- 85 sition indicated in Figs. 1 and 2 of the draw- ings. When it is desired to clean the brush the end of the sleeve 12 is engaged and the sleeve pushed longitudinally of the square rod 7 and the pins operating in the spiral 90 grooves 6 and 6' will rotate the rods 3 and 3' and throw the extensions 4 and 4' into the position illustrated in Fig. 4 of the drawings whereby the bristles will be separated. The 95 bristles may then be cleaned and when the sleeve is released the coil spring 15, which has been compressed by the movement of the sleeve, will expand and return the sleeve into its original position and the rods will be ro- 100 tated to bring the bristles adjacent the bris- tles 9.

Having fully described my invention what I claim as new and desire to secure by Let- 105 ters Patent, is:

1. A tooth brush comprising a casing, a stationary rod extending longitudinally of the casing and beyond one end thereof, rods rotatably mounted in the casing on each side of the stationary rod and one end of the ro- 110 tatable rods extending beyond one end of

said casing parallel with the extended end of the stationary rod, bristles connected to each of the rods at the ends of the extended portions, and means carried by the stationary rod for rotating the rotatable rods.

2. A tooth brush comprising a casing, a stationary rod extending longitudinally of the casing, and beyond the end thereof, rotatable rods mounted on either side of the stationary rod and extending beyond the end of the casing, said rotatable rods being both provided with spiral grooves, bristles connected to the rods, a bar slidable on the stationary rod, and projections carried by the bar and engaging the spiral grooves of the rotatable rods for rotating the same.

3. A tooth brush comprising a casing, a stationary rod extending longitudinally of the casing and beyond the end thereof, rods rotatably mounted in the casing on either side of the stationary rod, said rotatable rods having spiral grooves therein, bristles secured to the ends of the rods, a sleeve carried by the stationary rod and slidable longitudinally thereof, a cross bar connected to the sleeve, and projections carried by the cross bar and engaging the grooves in the rotatable rods for causing rotation thereof when the sleeve is actuated.

30 4. A tooth brush comprising a casing, a stationary rod extending longitudinally of the casing and beyond the end thereof, a rotatable rod mounted in the casing on either side of the stationary rod and extending beyond the end of the casing, said rotatable

rods being provided with spiral grooves, bristles connected to the rods, a sleeve longitudinally movable on the stationary rod, a cross bar connected to the sleeve, projections on the cross bar engaging the spiral 40 groove in the rotatable rods, and a spring surrounding the stationary rod between the end of the casing and longitudinally movable sleeve.

5. In a tooth brush, a casing, a rod fixedly 45 secured in said casing and extending longitudinally thereof, rods rotatably mounted in the casing adjacent each side of said fixed rod and disposed in parallelism therewith, said rotatable rods being provided with spiral grooves, a cross bar slidable on said fixed rod and provided with projections engaging into the grooves of said rotatable rods so as to cause rotation thereof in opposite direction when the cross bar is actuated, means 50 for normally forcing the cross bar toward one end of said casing, and means operable exteriorly of the casing for forcing the cross bar toward the other end of said casing so as to cause predetermined rotary movement of 60 the rotatable rods, the distance of rotation in either direction being limited by the projections on the cross bar engaging the ends of the grooves.

In testimony whereof I affix my signature 65 in presence of two witnesses.

OTIS J. WISE.
